Primary Examiner — Cathy A MacCormac(74) Attorney, Agent, or Firm — Barnes & Thornburg LLP(57) CLAIM

The ornamental design for a shelter, as shown and described.

DESCRIPTION

FIG. 1 is a left side perspective view of one side of a shelter showing my new design,

FIG. 2 is a top perspective view thereof,

FIG. 3 is a rear perspective view thereof,

FIG. 4 is a top, right side and rear perspective view thereof,

FIG. 5 is a front perspective view thereof,

FIG. 6 is another perspective view of FIG. 4 showing the shelter opened; and,

FIG. 7 is a front perspective view of, FIG. 6.

The bottom view of the design is plain. The illustrations of the design are not to depict any particular color.
